UNITED STATES PATENT OFFICE.

HOWARD S. CRAVER, OF CHICAGO, ILLINOIS, ASSIGNOR OF ONE-HALF TO HENRY S. JUDD, OF CHICAGO, ILLINOIS.

WASHING MACHINE.

Application filed September 29, 1922. Serial No. 591,234.

To all whom it may concern:

Be it known that I, HOWARD S. CRAVER, a citizen of the United States, residing at Chicago, in the county of Cook and State of Illinois, have invented a certain new and useful Improvement in Washing Machines, of which the following is a specification.

My invention relates to washing machines and is particularly adapted for that type of machine in which the clothes engaging elements have a vertical movement and also an intermittent rotary movement. An example of the general type is shown in my prior Patent No. 1,361,228 granted December 7th, 1920. Such machines are sometimes referred to as "vacuum" machines, being provided with a plurality of "vacuum cups" which face downward in the clothes receptacle and are operated by a vertical shaft which reciprocates vertically and also has an intermittent rotary movement which causes the cups to progress intermittently in a circular path concentric with the shaft. The shaft passes up through the bottom of the clothes receptacle and through a center post or sleeve which is stationary and forms a guide for the shaft. The progressive or rotary movement of the cups sometimes tends to wrap the clothes around the center post, which is very apt to tear them, and various expedients have been employed for avoiding this objection. In my aforesaid prior patent I have provided means for periodically reversing the direction of rotation of the cups so that if the clothes start to wind around the post they will soon be unwound from it. That machine employed a ratchet wheel having teeth facing in both directions and a self reversing pawl which would act upon one set of teeth for a while and then upon the other set, thus producing a periodic reversing in the direction of rotation of the cups. While that machine accomplished the ultimate object in a practical and efficient manner, nevertheless the ratchet was a positive acting device and forced the cups to rotate even when there might be a disadvantage in their doing so. Also, the ratchet produced a clicking noise, which was usually slight, but nevertheless perceptible. The object of my present invention is to provide an impositive connection between the shaft

and the driving mechanism so that if at any time the resistance to the rotary action of the cups become excessive, the cups may cease their rotary movement until the resistance is reduced to a proper degree. In my machine the continued vertical movement of the cups usually soon frees the clothes so that the action will be resumed without any attention on the part of the operator. Another characteristic is that the operator may hold the cups against rotary movement without necessitating stopping of the machine. Another object is to provide a construction which will operate silently, avoiding even the slight click which is audible in the machine of my former patent.

I obtain my objects by the mechanism illustrated in the accompanying drawings, in which—

Figure 1 is an assembly view of a washing machine embodying my invention. The clothes receptacle is shown in diametral section.

Figure 2 is a side elevation of the friction clutch which I employ for transmitting rotary movement to the shaft. The clutch is shown in diametral section and the figure also shows certain associated parts.

Figure 3 is a view analogous to Figure 2 but looking towards the left in Figure 2.

Figure 4 is a plan section on the line 4-4 of Figure 3.

Figure 5 is a side elevation of the parts shown in Figure 3 but showing said parts in changed position.

Like numerals denote like parts throughout the several views.

According to the design which I have chosen for illustrating the invention, the clothes receptacle 1 is cylindrical and is apertured at the center of the bottom to accommodate the main shaft 2 which passes up through it. Surrounding the shaft is a stationary center post or tube 4 which prevents leakage and forms a guide for the shaft. Near the upper end of shaft 2, above post 4, are horizontal arms 6 which carry vacuum cups 8. These are known elements in washing machines and the design may be considerably altered without changing the principle of operation.

Near its lower end shaft 2 has a collar 10

which is pinned or otherwise rigidly secured to it. This collar not only carries the shaft but excludes water from the parts beneath. A friction disc 12 encircles the shaft and is provided with a hub 14 which forms a support for the collar, and hence for the shaft and parts carried thereby. This disc faces downward and is loosely mounted on the shaft. By preference it has a depending marginal flange 16. A gasket 18 having a high frictional co-efficient encircles the shaft beneath disc 12. It may be regarded as a clutch lining and may assume various forms and consist of various component elements. Brake and clutch linings are well known and various types may be selected for use in my mechanism. This brake lining may be entirely omitted if desired. The upper disc 12 and lining 18 rest upon a lower friction disc 20 which faces upward and is splined upon the shaft in the sense of being vertically movable along it but connected to it in such manner as to impart a rotary movement to it. According to the design shown, a pin 21 passes through the shaft and projects laterally from it and slides in vertical notches 22 in the sides of the hub 24 of the disc. One of the advantages of thus notching the disc hub is to compensate for wear in the lining 18. Another object is to enable the lower disc to move toward and from the upper disc to vary the pressure against it.

Disc 20 is supported upon a collar 26 which is loosely mounted on shaft 2 and is itself supported by pins 28 projecting from the side of the collar and journaled in the outer end of the bifurcated lever 30. A washer 29 is supported by a nut 31 which screws on to the lower shouldered end of shaft 2 and limits the amount of vertical play of collar 26 lengthwise of the shaft. It will be evident from the foregoing that the shaft and fixed collar 10 rests upon the upper disc 12, which in turn rests upon the lining 18 which is supported by the lower disc 20. Disc 20 rests upon the collar 26 which is supported by lever 30. The upper disc is loosely mounted on the shaft, while the lower one is fastened to it (although slidably) and is rotatable upon collar 26 as a step bearing. Consequently the shaft is controlled vertically by the collar 26 and lever 30 but is free to rotate in its step bearing. Also it is evident that normally there will be a greater amount of friction between the two discs 12 and 20 than between the disc 20 and its supporting collar 26 (the latter usually having its upper surface lubricated). Hence when the weight of the shaft presses the upper disc down toward the lower one there will be a clutch action and the shaft can be rotated by rotating the upper disc. If, however, the shaft should be lifted slightly, or the upper disc should otherwise be relieved of the weight of the shaft, there would be

no appreciable clutching action and a rotary movement of the upper disc would not be able to produce a rotary movement of the shaft—especially if the tub 1 contained water, which would offer a certain amount of resistance. Hence the machine may be considered as having a clutch which will be in active condition when subjected to the weight of the shaft and will be in non-active condition when relieved of the weight of the shaft.

Lever 30 has a fulcrumed pin 32 at its opposite end, which is slidingly mounted in a bracket 34 having a horizontal slot 36 as shown in Figure 1. This arm or lever 30 is caused to swing up and down in a vertical plane by a connecting rod 38 pivotally connected at its lower end between the ends of lever 30 and at its upper end to gear wheel 40 at a point distant from the center, so as to obtain an eccentric action. Gear wheel 40 is driven by any suitable gearing and power mechanism. In the illustrated design it meshes with a pinion 42 secured to a sheave 44 driven by a belt 46. The belt is driven by a sheave 48 secured to the shaft 50 of a motor 52. It will be evident that when the motor is operating and the gear wheel 40 is rotating the lever 30 will swing up and down in a vertical plane about the fulcrumed pin 32 as an axis. This will cause the collar 26 to travel up and down in a vertical direction.

The swinging movement of lever 30 is availed of to impart a limited angular movement to disc 12, first in one direction and then the other. This is accomplished through the agency of the clutch mechanism hereinabove described. While the particular design may be considerably varied I have shown a pin 54 which projects from the side of lever 30 at a point distant from the pin 28 as best shown in Figures 2, 3 and 5. This works within a slot 56 formed between two fingers 58 which depend from and are preferably integral with the disc 12. By comparing Figures 3 and 5 of the drawings it will be evident that the swinging movement of the lever 30 will produce a movement in pin 54 having a horizontal component. This will produce a limited angular movement of the disc 12, first in one direction and then in the other, at the same time that the disc is traveling vertically approximately in unison with the shaft 2. The lever has a plurality of apertures 57 located at different distances from the pin 28 to receive pin 54 and thus vary the eccentricity or throw of oscillatory disc 12.

In practice, as the lever 30 vibrates up and down it will produce a corresponding vertical movement in the collar 26. This collar supports the lower friction disc 20, which in turn supports the lining 18 which supports disc 12 which supports collar 10, which sup-

ports shaft 2. The total length of parts 26, 22, 18 and 12 is slightly less than the distance between the collar 10 and the washer 29; hence slight vertical play is provided for. Let it be assumed that the clothes receptacle is partially filled with water and clothing. It will be evident that the upward movement of collar 26 produces a corresponding upward movement of the shaft 10 and vacuum cups. The resistance of the water and clothes to the upward movement of the cups adds to the apparent weight of the parts resting upon collar 25; consequently as the parts move upward the pressure of the two friction discs towards each other is increased. In other words, during the upward movement not only does the weight of the disc 12 and supported parts create a resistance to the upward movement 20 of the lower disc but in addition the resistance of the contents of the clothes receptacle, as well as the inertia of the supported parts. The consequence is that during the upward movement there is abundant frictional engagement between the two elements 25 of the friction clutch to transmit the angular movement of the upper disc 12 to the lower disc 20 and hence to the shaft. On the downward movement the action is reversed for the reason that the resistance met 30 by the cups in acting upon the clothes is more than sufficient to support the weight of the cups and shaft, and the lever 30 needs positively force the shaft downward. Under 35 these conditions the collar 26 actually presses downward upon washer 29, and as there is a slight play or lost motion it follows that the lower disc 20 descends of its own weight sufficiently to release the pressure between the two discs. Consequently 40 the return angular movement of disc 12 is without effect upon the lower disc and imposes no angular movement to it. The pressure of the upper disc 12 upon the friction lining 18 is no greater than the weight of the upper disc, which is negligible so far as its ability to rotate the lower disc is concerned. Thus on the up-stroke the resistance 45 met by the cups is added to the weight of the parts carried by disc 12 whereas on the down stroke the resistance met by the cups is subtracted from the weight of the parts, the result being a minus quantity so to speak, and thus relieving the lower friction disc of 50 any pressure other than that due to the weight of the upper disc itself. Thus the clutch, which is composed of said discs, is effective only in one direction, and the result is an intermittent rotary or step by step 55 movement of the cups.

It will be seen that in my machine there is an impositive connection between the vacuum cups and those elements which rotate them, and in consequence if the clothes should 60 become wrapped around the center post or

if for any other reason the rotary movement of the cups is opposed to an unusual degree they will stop rotating until the opposition ceases. Another advantage of this impositive connection between the driving mechanism and the cups is that the operator by grasping one of the cups or one of the supporting arms may hold them against rotation without otherwise stopping the machine, thus enabling him to inspect the contents of the machine or remove or add to the amount of clothing in the receptacle.

By varying the degree of roughness of the opposing faces of the friction disc or by varying the character of the intervening friction lining 18, the amount of opposition necessary to stop the progressive angular movement of the cups may be regulated. In practice this factor is such that the clothing, if it gets wrapped around the center post will 85 stop the progressive movement of the cups before the clothing becomes damaged.

It will be noted that the cups face downward and are convex on their upper surfaces. This adds still further to the effect, for it will be evident that under these conditions the resistance to downward movement will be greater, considering the water alone, than the resistance to upward movement. This 90 and the fact that the clothes are usually beneath the cups still further insures that the resistance to downward movement will be sufficient to release the clutch.

Another advantage in my present construction is that it is substantially noiseless. The play between the collar 10 and washer 29 need be hardly perceptible to enable the clutch to release. For the purpose of illustration I have shown in Figure 3 a perceptible space between the washer 29 and the lower end of collar 26 and in Figure 5 a perceptible space between the collar 10 and the upper end of hub 14. This is to illustrate the principle of action and is slightly exaggerated. In any event, the play need not be so great as to produce any appreciable amount of noise. Consequently even the sound of a pawl on ratchet teeth is eliminated. Again, while the pin 54 is loose in slot 56 the amount of play may be reduced to a very small quantity, thus avoiding any appreciable knocking sound when the pin reverses its direction of motion horizontally. While I have shown the discs 12 and 20 as having 105 substantially flat faces, it will be understood 110 that these may be varied according to well known principles of friction clutch construction.

Having thus described my invention what I claim as new and desire to secure by Letters Patent is:

1. A washing machine having a clothes receptacle, a vertical shaft provided with clothes engaging elements, the shaft being 120 movable vertically and angularly, a power 130

device for supporting the shaft and reciprocating it vertically, and a clutch interposed between the shaft and the supporting power device and controlled by the variations in pressure of the shaft on said supporting power device, said clutch including an angularly movable driving element and a cooperating angularly movable driven element connected to the shaft for moving it angularly.

2. A washing machine having a clothes receptacle, a shaft adapted to rotate and to reciprocate longitudinally, clothes engaging elements carried by said shaft a friction element having a limited angular movement backward and forward, a second friction element adapted to cooperate with the first and positively connected to the shaft for rotating it, and a power device for moving the second friction element into and out of operative engagement with the first and simultaneously move the shaft longitudinally.

3. A washing machine having a clothes receptacle, a vertical shaft movable vertically and angularly, clothes engaging elements carried by said shaft, a friction element supporting the shaft, means for imparting to it a limited angular movement back and forth about a vertical axis, a second friction element supporting the first friction element and capable of imparting angular movement to the shaft, and a vertically reciprocating power element for supporting the second friction element and reciprocating it vertically, said second friction element being rotatable independently of said power element.

4. A washing machine having a rotatable and longitudinal reciprocatable vertical shaft provided with a clothes engaging element, an upper friction disc facing downward and adapted to support the weight of the shaft and having a limited angular movement back and forth, the shaft being rotatable independently of said disc, a second friction disc beneath the first facing upward and adapted to support it, the second disc being splined to the shaft, and a power device for supporting the second disc and alternately raising and lowering it, the second disc being rotatable independently of said power device, and said discs being co-axial with the shaft.

5. A washing machine having a clothes receptacle, a shaft passing up through the bottom of the receptacle, the shaft being vertically and angularly movable and being provided with clothes engaging elements, a clutch including two friction discs, one of which is loosely mounted on the shaft and the other is connected to the shaft for rotating it, one of said discs being located above the other, means for moving the loosely mounted disc angularly back and forth, a bearing for the lower disc, and means for moving said bearing up and down.

6. A washing machine having a clothes receptacle, a shaft passing up through the bottom of the receptacle, the shaft being vertically and angularly movable and being provided with clothes engaging elements located at a distance from the shaft, an upper friction disc loosely mounted on the shaft, means for moving the disc angularly back and forth, a second friction disc facing the first and splined to the shaft, a collar loosely mounted on the shaft beneath the second disc for supporting it, and means for reciprocating the collar vertically.

7. A washing machine having a clothes receptacle, a shaft passing up through the bottom of the receptacle, the shaft being vertically and angularly movable and being provided with clothes engaging elements, a clutch including two friction discs, one of which is loosely mounted on the shaft and the other is connected to the shaft for rotating it, one of said discs being located above the other, and a power lever swinging in a vertical plane, said lever being adapted to support the lower disc and adapted to oscillate the loosely mounted disc.

8. In a washing machine, a reciprocatory vertical operating shaft, clothes engaging elements carried by said shaft and compelled at all times to move angularly with it, and means for moving said shaft vertically and angularly, including a friction clutch adapted to be thrown "in" and "out" by the resistance of the shaft to vertical movement.

9. In a washing machine a reciprocatory vertical operating shaft, clothes engaging elements carried by said shaft and compelled at all times to move angularly therewith, a power device for vertically reciprocating the shaft, and a friction clutch including two discs, the first of which supports the shaft and the second supports the first, the second disc being carried by the power device and one of said discs being positively connected to the power device to be moved angularly by it.

10. A washing machine having a clothes receptacle, a vertical reciprocating shaft, vacuum cups mounted thereon, a power device including a member moving up and down, and a clutch having a first element for rotating said shafts and slideable thereon, and a second element for supporting said shaft and rotatable independently thereof, said first element being connected to said power device to be moved up and down by it into and out of engagement with said second clutch member when the latter is retarded by the resistance of the contents of the clothes receptacle, said second clutch member being adapted to be oscillated by said power device.

11. A washing machine having a clothes receptacle, a vertical shaft provided with clothes engaging elements, the shaft being

movable vertically and angularly, a power device for reciprocating the shaft vertically, an eccentric on the power device, and a pair of cooperating clutch members, one of which is connected to the shaft for rotating it and the other is movable relatively to the shaft and is adapted to be oscillated by said eccentric, the upward movement of the power device moving said clutch members toward each other and the downward movement moving them away from each other.

In witness whereof, I have hereunto subscribed my name.

HOWARD S. CRAVER.
